DESIGN FOR A HOOP-ROLLING STICK

Robert H. Carter, Huntington Park, Calif.

Application May 1, 1940, Serial No. 92,061

Term of patent 7 years

To all whom it may concern:

Be it known that I, Robert H. Carter, a citizen of the United States, residing in Huntington Park, in the county of Los Angeles and State of California, have invented a new, original, and ornamental Design for a Hoop-Rolling Stick, of which the following is a specification, reference being had to the accompanying drawing, forming part thereof.

Figure 1 is a side elevational view of a hoop-rolling stick, showing my new design; and
Figure 2 is an edge elevational view thereof.

I claim:

The ornamental design for a hoop rolling stick, substantially as shown.

ROBERT H. CARTER.
